Primary Examiner — Elizabeth J Oswecki(74) *Attorney, Agent, or Firm* — Craig A. Deutsch(57) **CLAIM**

The ornamental design for an ear muff attachment housing, as shown and described.

DESCRIPTION

FIG. 1 is a perspective view of an ear muff attachment housing showing our new design;

FIG. 2 is a front view thereof;

FIG. 3 is a rear view thereof;

FIG. 4 is a left side view thereof, the right side being a mirror image thereof;

FIG. 5 is a top view thereof; and,

FIG. 6 is a bottom view thereof.

Broken lines form no part of the claimed design, and any shading is provided to illustrate contour only and is not an indication of texture, gloss, etc.
